G. E. LINT.

WINDOW FRAME AND SASH.

(Application filed Mar. 10, 1900.)

(No Model.)

A technical drawing of a vertical structure, likely a pipe or tube assembly. The structure is labeled with various letters and numbers:

- A**: A horizontal line near the top of the structure.
- B**: A bracket-like component at the top, with sub-labels **B²** and **B'**.
- C**: A bracket-like component in the middle, with sub-labels **C²** and **C'**.
- D**: A bracket-like component at the bottom, with sub-labels **D'** and **D²**.
- 3**: A horizontal line near the bottom of the structure.
- A'**: A bracket-like component on the right side, with sub-labels **A** and **B**.
- B²**: A bracket-like component at the very bottom, with sub-labels **B** and **B²**.

The drawing uses various line styles and hatching to differentiate parts, such as solid lines for main outlines and dashed lines for internal features. The labels are placed to the left or right of the corresponding parts.

UNITED STATES PATENT OFFICE.

GEORGE E. LINT, OF YORK, PENNSYLVANIA.

WINDOW FRAME AND SASH.

SPECIFICATION forming part of Letters Patent No. 651,465, dated June 12, 1900.

Application filed March 10, 1900. Serial No. 8,208. (No model.)

To all whom it may concern:

Be it known that I, GEORGE E. LINT, a citizen of the United States, residing at York, in the county of York, State of Pennsylvania, 5 have invented certain new and useful Improvements in Window Frames and Sashes, of which the following is a specification, reference being had therein to the accompanying drawings.

10 This invention relates to a window frame and sash, and particularly to a construction wherein a frictional contact with the frame is utilized to maintain the sash at different positions.

15 The invention has for one of its objects to provide an improved construction of sash adapted to coöperate with a frame having a beveled or inclined surface. Heretofore it has been old to bevel both the surface of the 20 frame and the contacting face of the sash; but in these constructions the parts became wedged together when the sash was lowered and rendered the raising of the same difficult, while after it was raised there was no 25 frictional contact to retain it in a raised position.

The present improvement is accomplished by means of a yielding incline upon one face of the sash adapted to travel upon the inclined way in the frame and normally held 30 under sufficient tension to maintain the sash in any position.

A further object of the invention is to provide an improved construction of sash in 35 which the parting strip or rail presses against one side of the sash at the mid-rail, while the opposite side of the sash is held under spring tension by means of the yielding wedge and strip.

40 Other objects and advantages of the invention will hereinafter appear in the following description, and the novel features thereof will be particularly pointed out in the appended claims.

45 In the drawings, Figure 1 is an elevation of the invention with parts in section. Fig. 2 is a vertical section thereof. Fig. 3 is a horizontal section on the line 3 3 of Fig. 1. Fig. 4 is an enlarged detail section. Fig. 5 is a 50 detail perspective of the lower end of the

wedge-strip; and Figs. 6, 7, and 8 are views similar to Figs. 1, 2, and 3, respectively, showing the application of the invention to storm-sashes and screens.

Like letters of reference indicate like parts 55 throughout the several figures of the drawings.

In the drawings the letter A indicates the window-frame, which may be of any suitable size or configuration and is provided with 60 the usual ways A', within which the sashes B are adapted to slide. The ways within the frame are beveled outwardly toward their lower portion, as shown in Fig. 1. In order to maintain a constant frictional contact between the sash and the frame for the purpose of maintaining the former at any desired elevation, a wedge-strip C is provided, which is pivoted at its lower end by means of an angular pivot C', fitting loosely a socket 70 of similar shape. This prevents any longitudinal or lateral movement of the strip C, but permits the same to incline outwardly, forming a bevel face to the sash, corresponding to the inclination of the way A' upon the 75 frame. This strip is held constantly under tension by means of a spring C² and prevents the sash from becoming tightly jammed at the inclined lower portion of the frame. The strip furthermore holds the sash against any 80 rattling or other movement, and when the sash is raised the strip will retain the same in its position. In the present form of the invention it is only found necessary to apply this strip to one side of the sash; but it may 85 be applied to both, if desired, and the ways for both of the sashes are similarly constructed.

In order that the sash may be held by substantially-equal pressure upon opposite sides, 90 and thus travel in a straight course, the parting-beads D are yieldingly mounted within the frame A — for instance, by means of springs D' behind the same—and these beads press against a face or shoulder B' at the mid-rail of the sash, thus holding the same under yielding tension and preventing the frictional resistance which would be caused by the strip C if the sash were forced by the same against a rigid face at the opposite side of the frame. 95 100

The shoulders B' upon the sashes are located at opposite sides by forming the mid-rail with an inclined face, and one of the parting-beads D bears against each of the sashes at the 5 meeting-rail. It may be stated that the beads D are provided with springs D' at suitable points throughout their length in order that they may be pressed outward with an equal pressure, and for the purpose of holding the 10 bead in position at the end of the sash farthest from the meeting-rail a pin or lug B^2 is provided and travels in contact with the face of the bead D . It is also proposed to apply the yielding wedge or strip C to other 15 than the window-sashes proper, as shown at B . For instance, as illustrated in Figs. 6, 7, and 8, storm-sashes E may be located within the window-frame and provided with spring strips or wedges E' , similar to those herein- 20 before described, which strips are adapted to ride upon suitable ribs or ways formed in the frame A , and these storm-sashes are independently mounted, so that they may be freely moved when access is desired to the 25 main window-sashes B . The holding strips or beads D and the construction of mid-rail with the shoulder B' are provided in these modifications of the invention. If desired, a screen F may be removably located upon 30 the outer portion of the window-frame, as shown in Figs. 6, 7, and 8, and may be mounted upon strips or beads F' . The screen-frame F is provided upon opposite sides with spring-strips F^2 , by means of which the frame 35 may be placed in position and the joint between the strip and the frame proper may be suitably covered by means of an overlapping flap F^3 of any suitable material. It will be obvious from the construction shown that the 40 different parts of the window may be removed whenever found desirable—for instance, the storm-sashes removed during the warmer weather or the screens during the winter season. It will be obvious that the sashes may 45 be easily operated and held at their adjustments without rattling by the construction described.

From the foregoing description of the construction of the invention the operation will 50 be clearly understood, and it need only be stated that the use of the spring wedge or strip pivotally mounted at its lower end prevents the jamming and wedging of the window when in its lowered position, which is 55 common with those constructions embodying an inclined way in the frame. This construction of way, however, is desirable, as when the window is lowered it is tightly held against rattling or other movement due to the pressure of the air thereon, and by overcoming the difficulties heretofore existing a very desirable construction of sash is provided. Furthermore, in the construction heretofore used when the window is raised to the wider portion 60 of the inclined way there is no holding means by which it may be retained in posi-

tion, and it must be secured by some independent device. The spring strip or wedge herein used exerts such a constant tension on the way as to hold the window at any desired 70 position, and this action is materially improved by the use of the spring B , bearing against the sash to cause the same to travel in a straight path. It may here be stated that the well-known construction of spring-strip 75 at the side of a sash yieldingly held at both ends is not adapted for use in my invention, as it is very difficult to cause the same to assume the inclined position attained by the use of the pivot and single spring herein illus- 80 trated.

It will be obvious that changes can be made in the details of construction and operation without departing from the spirit of the invention as defined by the appended claims. 85

Having described my invention, what I claim is—

1. In a window frame and sash, the combination with the frame having an inclined way, of a sash provided with a wedge or strip 90 having its lower end in contact with the sash and its upper end forced away therefrom and yieldingly held in contact with said way; substantially as specified.

2. In a window frame and sash, the combination with the frame having an inclined way, of a sash provided with a wedge or strip yieldingly held in contact with said way, and a spring-pressed bead bearing against said sash at the opposite side from said strip; substantially as specified. 95

3. In a frame and sash, the combination of a frame having an inclined way, of a sash provided with a strip pivoted at its lower portion in said sash, and a spring above said 105 pivot to force said strip against said way; substantially as specified.

4. In a frame and sash, the combination of a frame having an inclined way, of a sash provided with a strip pivoted at its lower portion in said sash, a spring above said pivot to force said strip against said way, and a yielding bead bearing against a shoulder upon 110 said sash upon the opposite side from said strip; substantially as specified. 115

5. In a frame and sash, the combination of a frame having an inclined way, of a sash provided with a strip pivoted at its lower portion in said sash, a spring above said pivot to force said strip against said way, a yielding bead bearing against a shoulder upon 120 said sash upon the opposite side from said strip, and a lug carried by said sash and bearing against said bead; substantially as specified.

6. In a window frame and sash, the combination with inclined ways for the independent sashes thereof, spring-pressed strips or wedges engaging said ways, mid-rails for said sashes each having a shoulder and independent spring-pressed beads bearing against each 125 shoulder at the side opposite to the spring-pressed strip; substantially as specified. 130

7. In a window frame and sash, the combination with a way, of a spring-pressed strip having at its lower portion an angular pivot-pin adapted to seat in a similar recess in said sash, and a spring to force the upper portion of said strip outward; substantially as specified.

In testimony whereof I affix my signature in presence of two witnesses.
